UNITED STATES PATENT OFFICE.

THOMAS M. DEVINE, OF CLEVELAND, OHIO, ASSIGNOR TO THE OHIO VARNISH COMPANY, OF CLEVELAND, OHIO, A CORPORATION OF OHIO.

PAINT AND VARNISH REMOVER.

1,024,926.

Specification of Letters Patent.

Patented Apr. 30, 1912.

No Drawing.

Application filed August 21, 1911. Serial No. 645,231.

To all whom it may concern:

Be it known that I, THOMAS M. DEVINE, a citizen of the United States, residing at Cleveland, in the county of Cuyahoga and 5 State of Ohio, have invented a certain new and useful Improvement in Paint and Varnish Removers, of which the following is a full, clear, and exact description.

This invention relates to a composition 10 of matter adapted to be applied to a painted or varnished surface and so dissolve or destroy the paint or varnish that it may be readily removed.

One of the objects of the invention is to 15 give the remover such a character that a paint or varnish attacked by it may be washed clean from the wood with water.

Another object is to provide in the 20 varnish remover a protecting coating adapted to not only retard evaporation as it is being applied, but, by standing in a layer above the volatile constituents, prevent any rapid evaporation when the material is standing in an open vessel.

25 Other objects are to render the remover harmless to the hands of the operator and non-poisonous.

I accomplish the above objects by providing a water soluble caustic, a series of paint 30 or varnish solvents and a thickener, the whole combination being in such proportions as to be very effective in attacking and loosening the constituents of paint and varnish without being so strong as to injure 35 either the fiber of the wood or the hands of the operator.

The preferred composition for my 40 remover consists of caustic soda or potash, water, alcohol, benzol, carbolic acid, and spermaceti. I prefer to use these in substantially the following proportions, namely: 4 oz. caustic soda or potash, 2 oz. water, 6 pts. alcohol, 8 oz. carbolic acid, 5 pts. benzol, 3 oz. spermaceti.

45 The caustic soda or potash is preferably first dissolved in the water. To this is added the alcohol and then the carbolic acid. 3 ounces of spermaceti is preferably melted and dissolved in the 5 pints of benzol and 50 then this mixture added to the former. If commercial caustic soda or potash is used there will be impurities in it in the form of carbonates, which do not interfere with the dissolving action, while on the other hand

they are of assistance in cleaning the surface of the wood. For the alcohol I prefer to use ordinary wood alcohol, though it is to be understood that other alcohols may be used. Ordinary commercial spermaceti, benzol and carbolic acid are employed.

55 When the mixture is made it is placed in glass jars or bottles and is ready for use. In this condition there is on top a distinct layer of a saturated solution of spermaceti and benzol. This layer, while in the jar, is 60 very effective in retarding the evaporation of the volatile constituents. Below the layer of spermaceti and benzol comes a mixture of the other constituents and so much of the benzol as is not holding the spermaceti 65 in the top layer. At the bottom of the vessel are the carbonates in the form of precipitates. Before using, the vessel is shaken to thoroughly mix the contents; the remover, which is quite fluid, is then applied 70 to the painted or varnished surface by a brush or rag; the surface is then preferably loosened by the action of a little steel wool, after which the remover and the disintegrated paint or varnish is washed off simply 75 with cold water, leaving the surface clean 80 and ready to be refinished.

The benzol, carbolic acid and alcohol are 85 all solvents for the constituents of paint or varnish and, being mixed together, act more vigorously than any of them alone. The water in the mixture facilitates the caustic going into the solution. The caustic soda or potash acts on some of the constituents 90 of the paint and varnish so that when the wash water is used saponification of the paint or varnish takes place and this saponified matter dissolving leaves a mixture 95 on the surface which may be readily washed off. The soap produced by the saponification also assists in cleaning the surface. The wash water and caustic raises the grain 100 of the wood just sufficiently to expel the filler, which is saponified by the caustic and wash water. The result is that simply cold water may wash the surface perfectly clean 105 of all traces of the paint or varnish and filler and of all greases or gums. This capacity of my remover to act on the paint or varnish so that not only the destroyed paint and varnish but the remover itself is entirely removed by the action of cold water is a very decided advantage over

paint and varnish removers which require more volatile liquids for the removal of them and the destroyed paint or varnish.

It should be noted that in my composition the water in the mixture reduces the solubility of the alcohol for benzol, and spermaceti being soluble in benzol and practically insoluble in alcohol, the spermaceti, with a portion of the benzol, forms a layer on top, as heretofore explained, the depth of this layer depending on the amount of water in the mixture. That is to say, increase in the water increases the amount of benzol which goes with the spermaceti in the top layer. After the contents are shaken up and allowed to stand, whatever benzol cannot be dissolved in the lower layer separates and rises with the spermaceti to the top in globules.

It will, of course, be understood that changes may be made in the proportions given. I have found that a small amount of ammonia, say one ounce, added to the formula stated somewhat increases the cleaning power of the compound, though ammonia is optional and may be used or not, as desired.

Having thus described my invention, what I claim is:

1. A paint or varnish remover, the constituent ingredients of which are a comparatively large proportion of alcohol and benzol and a comparatively small proportion of caustic soda or potash, carbolic acid, and spermaceti dissolved in a portion of the benzol and forming in the vessel a protective layer over the other constituents.

2. A paint or varnish remover consisting of caustic soda or potash, carbolic acid, alcohol and benzol, and spermaceti in a top protective layer.

3. A paint or varnish remover consisting of carbolic acid or its equivalent a solvent for paint or varnish and an evaporation retarder adapted to stand in the vessel dissolved in a portion of the solvent as a protective layer.

4. In a paint or varnish remover, the combination of a plurality of solvents for paint or varnish and a substance soluble in one of the solvents but not in another, the substance forming with its solvent a protective layer above the other solvent or solvents.

5. A water soluble paint or varnish remover consisting of solvents for paint or varnish constituents, a caustic alkali adapted to saponify with some of such constituents, and a substance soluble in one of the solvents and adapted to float therein on the rest of the solvents in the vessel and from a protective layer thereover as well as to retard evaporation when applied.

6. A paint or varnish remover consisting of caustic soda or potash, carbolic acid or its equivalent, alcohol and benzol, and a thickener in a top protective layer.

In testimony whereof, I hereunto affix my signature in the presence of two witnesses.

THOMAS M. DEVINE.

Witnesses:

ALBERT H. BATES,
J. B. HULL.
